UNITED STATES PATENT OFFICE.

JAMES RAYMOND HUBBARD, OF CHICAGO, ILLINOIS.

GOVERNING DEVICE FOR EXPLOSIVE-MOTORS.

No. 800,614.

Specification of Letters Patent.

Patented Sept. 26, 1905.

Application filed June 20, 1904. Serial No. 213,248.

To all whom it may concern.

Be it known that I, JAMES RAYMOND HUBBARD, a citizen of the United States, residing at Chicago, in the county of Cook and State 5 of Illinois, have invented new and useful Improvements in Governing Devices for Explosive-Motors, of which the following is a specification, reference being had to the accompanying drawings, forming a part thereof.

10 The purpose of this invention is to provide improved means for governing the action of an explosive-motor by means of controlling the supply of the explosive gas.

It consists of the features of construction 15 set out in the claims.

In the drawings, Figure 1 is a section axial with respect to the cylinder through the gas-inlet and controlling devices which constitute my invention. Fig. 2 is a detail bottom plan 20 of the portion of the structure containing the controlling devices. Fig. 3 is a section at the same plane as Fig. 1 through the controlling devices, having a slightly-modified structure.

I have shown the intake end only or head 1 25 of the cylinder, on which is mounted the gas-inlet valve-body 2, having the gas-inlet valve 3 opening inward with respect to the cylinder for admitting the supply of explosive fluid through the inlet-chamber 4, whose port 4^a is 30 connected with the carbureter. (Not shown.) The inlet-valve 3 has its stem 5 extending through the wall of the inlet-chamber 4 opposite the cylinder-head and connected by lever devices for multiplying motion with an auxiliary piston 6, playing in a vertical auxiliary cylinder 7, the top of which is provided 35 with a small air-inlet valve 8, which may be adjusted by the operator to permit any desired access of air or to close said valve entirely. A spring 9 is provided, tending to hold the piston 6 at the upper limit of its play in the cylinder 7, which is at the extreme 40 upper end of the cylinder close against the inner side of the top cap 7^a. Said top cap is hinged at one edge, so as to open freely upward and to seat by gravity, operating thus 45 as a check-valve opening outward with respect to said auxiliary cylinder. In Fig. 1 I have shown the preferred arrangement of said 50 auxiliary cylinder and piston with respect to the axis of the inlet-valve and of the cylinder, which involves the preferred arrangement of the lever connections from said inlet-valve stem to said auxiliary piston. Said connections comprise a short lever 10, fulcrumed 55 intermediate its ends on the rigid supporting

parts or framework of the inlet-chamber and auxiliary chamber, which are rigidly connected, the lower end of said lever 10 being pivotally connected with the upwardly-extending 60 short arm of the bell-crank lever 11, whose arm 12, extending substantially horizontally onward in the direction of the outthrust of the inlet-valve 8, is connected at its lower end by means of a short link 13 with the lower 65 end of the stem of the auxiliary piston 6. This connection, it will be observed, causes the inward or opening movement of the inlet-valve 3 to communicate to the auxiliary piston a downward or indrawing movement 70 proportioned to the opening movement of the inlet-valve, as may be determined by the proportions of the lever connections described. As illustrated, the purpose of the short lever 10 is merely to reverse the direction of motion, and it is pivoted at the middle point, and the upstanding arm of the bell-crank lever 11 is substantially one-third of the length 75 of the horizontal or onwardly-extending arm 12, so that the movement which the piston 6 80 derives from the opening movement of the valve 3 is three times as great as said movement of said valve. I do not limit myself to this particular proportion; but a multiplication of movement is essential to the action, 85 which may be understood to be as follows: When the piston makes its outward stroke for drawing in the gas-supply, the inlet-valve 3, being pulled off its seat by the suction, is resisted in such opening movement to the extent 90 that the resulting movement of the auxiliary piston 6 produces a partial vacuum above it in its cylinder 7. If there were no air-inlet, as would be the case if the valve 8 were closed, it will be seen that the resistance 95 offered by the auxiliary piston 6 to the opening movements of the inlet-valve 3 would be measured by the area of said auxiliary piston exposed to atmospheric pressure of fifteen pounds to the square inch, because the 100 piston being in contact at its upper surface with the under surface of the cap or upper end of the auxiliary cylinder 7 the slightest movement of said piston away from said surface would produce a total vacuum above it. 105 The valve 8 being open to a slight extent and permitting the entrance of air to a corresponding extent, such vacuum would be prevented to the extent that the air can enter, and if the movement of the auxiliary piston 110 is slow the air may enter through a very small opening past the valve 8 fast enough to pre-

vent any appreciable vacuum. In practice I have found that if the auxiliary piston has only the same rate of movement as the inlet-valve the slightest opening of the air-inlet valve 8, admitting the least supply of air to prevent vacuum, will permit the piston to move and the inlet-valve to open to an extent permitting almost a maximum supply of gas, and no appreciable effect in the way of control of the extent of the gas-inlet opening is obtained; but if the velocity of the withdrawing movement of the auxiliary piston is very much greater than that of the opening movement of the inlet-valve the retarding effect of a partial vacuum above the piston is obtained upon a very slight opening of the inlet-valve, and it becomes possible, therefore, to regulate the extent of said opening by regulation of the opening of the air-inlet valve 8. The ratio of three to one in the velocity of the auxiliary piston and inlet-valve is practical—that is, it is sufficient to give complete control of the movement of the gas-inlet valve by means of the air-supply admitted through the air-inlet valve 8.

Since the gas-inlet valve must close promptly and without retardment by reason of the necessity of forcing out through a restricted aperture the air which may have been drawn in it through such aperture in the retarding opening movement of the gas-inlet valve, I make the top of the cylinder 7 as described for the purpose of operating as a check-valve, so that the air passes out with perfect freedom upon the return movement of the piston, which is caused by the spring 9, which operates by the lever connections described as a spring for seating the inlet-valve 3.

For keeping the auxiliary piston 6 lubricated in its cylinder I provide in said cylinder an angular oil-cup formed by the concentric flange 14, and I make said auxiliary piston in the form of an inverted cylindrical cup whose cylindrical wall enters said annular oil-chamber and dipping in the oil at each indrawing stroke carries up enough oil for its lubrication.

In the form shown in Fig. 3 one of the levers connecting the gas-inlet valve with the auxiliary piston is dispensed with and said valve-stem is connected directly to the downwardly-extending short arm of the bell-crank lever 11, whose onwardly-extending longer arm 12 is connected by the link 13 to the end of the piston-stem. This necessitates erecting the auxiliary cylinder 7 substantially wholly above the level of the upper side of the gas-inlet chamber 4, and thereby unduly extends the structure in this direction, or at least extends it inconveniently for certain purposes, and it is to avoid this undesired extension that I prefer to employ the structure shown in Fig. 1, which requires the short reversing-lever 10 in order to employ the bell-crank lever with its short arm extending up instead

of down from its fulcrum. I have shown the structure of Fig. 3 merely to make clear the reason for the preference for the structure shown in Fig. 1.

I claim—

1. In an explosive-motor, in combination with the gas-inlet valve, an auxiliary cylinder and piston therein connected with the gas-inlet valve, the connections being proportioned for multiplying the movement which the inlet-valve, in opening, transmits to the auxiliary piston, said auxiliary cylinder having beyond the piston a restricted air-inlet, and a check-valve opening outward for free outlet. 70

2. In an explosive-motor, in combination with a gas-inlet valve, an auxiliary vertical cylinder; an auxiliary piston operating therein, and connections from the gas-inlet valve to said piston for withdrawing it from the closed end of its cylinder when the inlet-valve opens, with a movement multiplied over that of the inlet-valve; a spring for upholding the auxiliary piston in its cylinder, said cylinder having a restricted air-inlet above the piston, and a valve for controlling the same at will, 80 and an outwardly-opening check-valve for permitting free outlet of air in the return upward movement of the piston. 90

3. In an explosive-motor, in combination with the gas-inlet valve, a gas-inlet chamber; an auxiliary cylinder rigid with said chamber beyond the same, the gas-inlet valve having its stem extended across said chamber and protruding through the remote wall thereof, said auxiliary cylinder being erected vertically opposite said remote wall, and being closed at the top; an auxiliary piston in said cylinder and lever connections from the protruding stem of the inlet-valve to said piston comprising a lever extending downward from the end of the piston, fulcrumed between its ends; a bell-crank lever having an upstanding short arm connected to the lower end of said first-mentioned lever, and an onwardly-extending long arm connected with the stem of the auxiliary piston; a cap which closes at the upper end of the cylinder, hinged at one side to operate as a check-valve opening upward; a restricted air-inlet for the cylinder through said cap; a valve for controlling said inlet, and a spring operating on said connected gas-inlet valve and auxiliary piston for seating the gas-inlet valve. 100

4. In an explosive-motor, in combination with the gas-inlet valve and gas-inlet chamber, an auxiliary cylinder erected vertically beyond the gas-inlet chamber and closed at the top; an auxiliary piston in said auxiliary cylinder; lever connections from the inlet-valve stem to said piston comprising a bell-crank lever having a longer and a shorter arm, the longer arm being connected to the piston-stem, and a lever fulcrumed intermediate its ends connected at one end with the shorter arm of the bell-crank lever, and at the other end 120 125 130

with the inlet-valve stem; a restricted air-inlet for the auxiliary cylinder at the upper end; a valve for controlling said inlet, and a check-valve opening outwardly from said auxiliary cylinder above the piston.

5. In an explosive-motor, in combination with the gas-inlet valve and gas-inlet chamber, a vertical auxiliary cylinder rigid with said chamber beyond the same and closed at its upper end; a piston reciprocating in said cylinder, said cylinder having a restricted air-inlet at the upper end and a valve to control the same, and having an outwardly-opening

check-valve; a spring which yieldingly resists the withdrawal of the piston downward 15 in said cylinder, and motion-multiplying lever connections from the gas-inlet-valve stem to the piston-stem.

In testimony whereof I have hereunto set my hand, in the presence of two witnesses, this 20 15th day of June, 1904.

J. RAYMOND HUBBARD.
